UNITED STATES PATENT OFFICE.

WILLIAM JAMES THOMAS, OF COVERDALE, PENNSYLVANIA.

COAL DRILL OR BORING MACHINE.

Application filed February 24, 1926. Serial No. 90,383.

This invention relates to a boring machine designed for use in mines, tunnels and the like, the general object of the invention being to provide a single post for holding the 5 drilling device, the post being adjustable as to length and having means for clamping it between the top and bottom walls of the tunnel or mine, with means for reversing the screw shaft which carries the drill so 10 that it is not necessary to back up the shaft to reset it after it has been fed its length through the nut member.

Another object of the invention is to provide means for adjusting the nut carrying 15 member on the post so that a plurality of holes may be bored without removing the post.

This invention also consists in certain other features of construction and in the 20 combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the several views, and in which:—

30 Figure 1 is a view showing the device in use.

Figure 2 is a plan view of the device.

Figure 3 is an edge view thereof.

35 Figure 4 is a section on line 4—4 of Figure 1.

Figure 5 is a section on line 5—5 of Figure 4.

40 Figure 6 is a detail view, partly in section, showing the means for connecting the screw shaft with the bit.

In these views, A indicates the supporting post of the device which is composed of the two sections 1 and 2 which are slidably connected together by the sockets 3, 45 one of which is carried at one end of each section and receives the opposite section. Each section is provided with a plurality of holes 4 so that the sections can be fastened together in adjusted position by the bolt 5 and its wing nut 6 and also by a threaded stud 7, on a bracket 8, and its wing nut 9. The stud also permits the bracket 50 to be rotated when the nut is loosened.

The lower end of the member 1 is formed 55 with a point 10 so that it will penetrate the

floor of the tunnel or mine, as shown in Figure 1, and a horizontal arm 11 is fastened to the upper end of the section 2 and has a threaded hole therein to receive a threaded shaft 12 which is provided with a pointed end to penetrate the ceiling of the mine. This shaft is provided with a handle 13 so that it can be rotated.

The bracket 8 is provided with a threaded hole 14 which is engaged by a screw shaft 15, each end of which is provided with a reduced part 16 of square shape in cross section. The shaft is adapted to be turned by a handle 17 which is provided with a plurality of square holes 18, any one of which is adapted to receive a square part 16 of the shaft so that the handle can be adjusted on the shaft. A coupling 19, having a square bore, is provided for connecting one of the reduced parts 16 with the 70 drilling bit 20, which is provided with a square part 21 to engage the bore of the coupling. This part 21 is of considerable length so that the coupling can be moved over the same to permit the shaft and bit 75 to be placed in alignment and then the coupling is moved over the reduced part 16 of the shaft to connect the parts together.

It will be seen that when the shaft 15 has been turned until one end nears the 85 post, it is simply necessary to loosen the screw 9, move the coupling 19 on to the shank 21 of the drill and remove the handle and then rotate the bracket 8 on its pivot formed by the stud 7 and thus reverse the 90 shaft, as shown by the arrows in Figure 1. Then the handle is placed on the reduced part 16 which is opposite to that part which the handle engaged before, place a longer bit in the hole and then couple this bit with 95 the shaft. Then the drilling can be resumed. By this arrangement, it is not necessary to unscrew the shaft 15. By placing the stud 7 in different pairs of holes 4 in the post A, a number of the holes can 100 be drilled in the tunnel head without moving the post. By making the post telescopic, it can be set up in tunnels of varying heights.

It is thought from the foregoing description that the advantages and novel features of my invention will be readily apparent.

I desire it to be understood that I may make changes in the construction and in the combination and arrangement of the several 110

parts, provided that such changes fall within the scope of the appended claim.

What I claim is:—

A boring machine comprising a telescopic upright, means for holding the parts of the upright in adjusted position, means for clamping the upright between the floor and ceiling of a tunnel, a bracket having a threaded hole therein, means for rotatably connecting the bracket with the upright, such means also permitting vertical adjustment of the bracket on the upright,

a screw shaft engaging the threaded hole in the bracket, said shaft having each end square, a handle having square holes therein for receiving either end of the shaft, a bit having a square stem and a coupling having a square bore for fitting over the stem of the drill and either square end of the screw shaft.

In testimony whereof I affix my signature.

WILLIAM JAMES THOMAS.
